UNITED STATES PATENT OFFICE.

WILLIAM SPARKS, THEODORE JOHNSON SCOFIELD, LLOYD ELMER JOHNSON, AND FRED WILLIAM BILLIG, OF JACKSON, MICHIGAN, ASSIGNEES TO THE SPARKS-WITHINGTON COMPANY, OF JACKSON, MICHIGAN, A CORPORATION OF OHIO.

SIGNALING DEVICE.

Application filed May 18, 1927. Serial No. 192,331.

This invention relates to certain new and useful improvements in signaling devices.

The main object of the invention is the production of a novel signaling device particularly designed for use on automobiles and capable of producing a comparatively loud signal that will carry long distances, and is of a musical tone, or a combination of musical tones, preferably of a harmonious character, and which device is so formed and arranged that the ornamental sound-emitting portion may be positioned on the exterior of the vehicle body and secured to the body, while the pressure producing apparatus and its driving means may be positioned at a distance from the sound-emitting portion, as for instance under the hood of an automobile where it is not ordinarily exposed to view. The securing means for the sound-emitting portion is of such a character that fluid under pressure can pass through it from the pressure producing means to the sound-emitting structure.

More detailed objects relate to the simplicity and strength of the structure and the detailed form, arrangement and association of the parts thereof, all as will more fully appear from the following description, taken in connection with the accompanying drawings, in which:

Figure 1 is an elevation of a device of this invention.

Figure 2 is a section on line 2—2, Figure 1.

Figure 3 is a section on line 3—3, Figure 1.

Figure 4 is a section on line 4—4, Figure 1.

Figure 5 is a section on line 5—5, Figure 1.

The structure as herein illustrated consists of a rotary electric motor —1— having its armature shaft substantially vertically disposed and the upper end wall —2— of the case of the motor is of substantially circular form and provided with a depending tubular boss —3— in which the upper end of the armature shaft —4— is journaled.

The lower end of the armature shaft —4— extends through an opening in the U-shaped case —7—, and may be provided with an adjustable bearing —5— carried by the end or cross-wall —6— of the U-shaped motor case —7—. The ends of the U-shaped motor case —7— are secured to the flanges —8— and —9— respectively formed upon the upper end wall —2—. The usual armature

—10—, pole pieces —11— and field coils —12— are provided.

The actual structure of the motor may vary widely, the essential being a means for producing rotary movement, and any form of electric motor may be utilized which is capable of driving a rotary compressor which constitutes a portion of the device, and for this purpose the end wall or head —2— is formed with a circular chamber or cylinder —14— on the side opposite the electric motor —1—, and this cylinder recess or chamber is eccentric with respect to the armature shaft —4—, and to the rotor shaft —15— which is aligned with the armature shaft —4—, and may be connected to the rotor —13— in any suitable manner, as for instance formed integrally with the rotor.

The rotor shaft extends into and is journaled in the boss —3— and may terminate a short distance above the upper end of the armature shaft —4—, and is connected to the armature shaft for simultaneous rotary movement, while permitting relative longitudinal movement in any suitable manner, as by a key —50— extending into slots formed in the adjacent ends of the rotary shaft, and the armature shaft for locking the two against relative rotary movement, the key being positioned at an intermediate point along the bearing —3—.

In effect, the rotor shaft —15— and the armature shaft —4— are a sectional armature shaft and for the purpose of the claims of this application may be so considered.

The armature shaft being concentric with the end head —2— and the rotor —13— being concentric with the armature shaft, the rotor is eccentrically positioned in the cylinder or chamber —14— by reason of the fact that the said cylinder is formed eccentrically in the end head.

The end head —2— is further formed with an air storage chamber —17— in this instance arranged concentrically with the wall of the cylindrical chamber —14— and extending around the cylindrical chamber throughout slightly more than one-half of its circumference. This storage chamber is in communication with the pressure side of the rotary pump through a port —18— in the wall of the chamber —14—, and through this port air under pressure

is ejected by the rotor —13— from the chamber —14— and for effecting this result the rotor —13— includes one or more, in this instance three movable blades —19— 5 slidably mounted in grooves or recesses in the rotor, and preferably spaced equal distances apart and adapted to be thrown out by centrifugal force as the rotor —13— is driven by the armature shaft —4—.

10 The compressor chamber —14— is formed with an air inlet —20— at the suction side of the compressor, and which air inlet penetrates the bottom wall of the compressor chamber, and leads into the casing —51— which 15 encloses the electric motor —1—. This casing is usually imperforate and for the purpose of admitting air to its interior, it is formed with a struck-up portion —52— interrupting the continuity of the casing wall and forming a passageway —53— leading to a passageway —54— through the flange —55— on the end head —2—, whereby air may be freely supplied to the inlet —20— of the compressor, and without the production of vacuum within 20 the casing —51—.

25 Mounted upon the upper end of the head —2— and covering the compressor chamber —14— and the storage chamber —17— is an end cap —80— secured to the head —2— in any suitable manner, as by screws —81—. This end cap is formed with a boss —82— formed with a conduit —95— leading to the storage chamber —17— and the wall of the conduit is interiorly threaded for the reception 30 of one of the threaded ends of a tubular elbow —83—, the opposite end of which is connected to a pipe —84— as by union —85—. In addition, the boss —82— is further formed with a lubricant-receiving chamber 35 —85— normally closed by screw —86— and adapted to contain lubricant-retaining material, such as felt or the like, the lower end of the lubricant chamber leading to and communicating with the compressor chamber 40 —14—.

45 The pipe —84— is connected at its end opposite the elbow —83— to a second elbow —87— as by union —88— and the opposite end of the elbow is threaded into the head portion of a tubular screw —89—, the opposite end of the tubular screw being threaded into the internally threaded base —90— of a hollow horn body —91—. The tubular screw —89— in connection with the base of the 50 horn-body —91— constitutes a means for connecting the sound-emitter portion of the structure to the wall —92— of a vehicle body such as an automobile body, and in order to effect the connection it is only necessary to 55 form an opening in the wall —92— of a size to receive the tubular screw —89—.

60 In assembling the parts the screw is passed through the opening in the wall —92— and is then threaded into the base —90— of the 65 horn-body —91— and suitable washers

—93— and —94— may be provided disposed upon opposite sides of the wall —92— and between the base of body —90—, and the head of the tubular screw —89—. In this manner 70 a rigid single point connection for the sound-emitting portion of the structure is provided and in which the fluid for actuating the sound-emitting devices passes thru this single point connection, i. e. through the tubular screw —89— into the horn body —91—.

75 The structure here illustrated is designed to include two sound producing structures, and except for the length of the projectors —60— these sound producing devices are of similar form, shape and structure, and a description of one constitutes a description of both. The projectors —60— differ in this illustration in that one of them is somewhat longer than the other for the purpose of producing different notes which by suitable adjustment of the devices can be made harmonious in character.

80 In each case the projector —60— has its rear end threaded into the front end of one of the bosses —59— on the horn body and a tube —61— is threaded into the boss so as to substantially contact with the rear end of the projector —60—, and this tube projects rearwardly from the boss —59—.

85 Each boss —59— has a circumferentially enlarged intermediate portion forming an annular chamber —62— surrounding the tube —61— and in communication with the respective conduits —58—. The rear end of each boss is internally enlarged with respect 90 to the front end and is threaded for the reception of an externally threaded tubular boss —63— formed concentrically at the base of a cup-shaped member —64— which may be locked in any desired position with respect to 95 boss —59— by means of lock nut —65—.

100 The internal diameter of the boss —63— is somewhat greater than the external diameter of the tube —61— so as to form an annular passageway around the tube leading from 105 chamber —62— to the interior of the cup-shape member —64—. The external wall of the cup-shape member —64— is externally threaded for cooperative engagement with the interiorly threaded flange upon a cup-shape cap —66—, and this cap —66— is formed with a radial shoulder —67— between which and the end of the cup-shape member —64— a thin metallic diaphragm —68— has its edge confined.

110 The size and arrangement of the parts is such that when the diaphragm is positioned, as described, it extends across and normally closes the rear open end of the tube —61— and preferably the rear open end of tube 115 —61— is flared, as indicated at —69—.

120 It is found that the air in the chamber between the diaphragm —68— and the cap —66— varies in pressure somewhat in accordance with the temperature to which the 130

device is subjected, thereby varying the pressure upon the diaphragm —68— which in turn effects the operation of the signaling device, and in order to maintain the device unit 5 form in operation, the cap —66— is provided with one or more openings —70— leading to the chamber between the diaphragm and the cap to permit the entrance of air to or the exit of air from said chamber to maintain a 10 normal pressure, irrespective of temperature changes.

These openings may, if desired, be covered on the inside by plate —71— and on the outside by disk —72— for appearance sake so 15 long as sufficient space is provided, as for instance by small grooves or passageways —73— for the escape or entrance of air.

In operation, when the armature shaft is rotated, air entering through inlet —20— is 20 compressed and ejected through outlet —18— into storage chamber —17—, and thence passes thru the hollow horn body —91— to the respective chambers —62— and thence through annular passageways —75— to the 25 interior of the cup-shape member —64— into contact with the front side of diaphragm —68—, whereby diaphragm —68— is caused to move slightly rearwardly to permit the escape of the air through the tube —61—.

30 The resiliency of the diaphragm and the variation in pressure, due to the escape of air, returns the diaphragm to the position where it closes or substantially closes the inlet to tube —61—, and the operation is then repeated, thereby causing a rapid vibration of 35 the diaphragm over the mouth of the tube —61—, producing and causing the projectors to emit a musical tone. The spacing and supporting member —76— may be interposed 40 between the end of the shorter projector —60— and an intermediate portion of the latter, and this spacing and supporting member may be formed with a groove for receiving the edge of the shorter projector and with 45 an inclined surface conforming to the external wall of the longitudinal projector.

By adjusting the cup-shape member —64— in the boss —59— a proper positioning of the diaphragm —68— can be effected to produce 50 the desired note, and the member —64— may then be locked in place by lock nut —65—.

From the above it will be apparent that the 55 ornamental sound-emitting portion of the structure including the projectors —60— and the diaphragm chambers and the horn body, are secured to a wall of the vehicle by a single point connection, and are positioned exterior of the vehicle body, while the motor and pump may be positioned at any point within 60 the vehicle body and the pipe —84— may be

made of a suitable length for predetermined installation. The end head —2— as shown, is formed with threaded openings —96— adapted to receive suitable attaching means for mounting the structure.

65

And altho we have shown and described a specific structure as constituting the perhaps preferred embodiment of the invention, we do not desire to restrict ourselves to the details of form, construction or arrangement 70 of the parts thereof, except as the same may be specifically included in the claims hereto appended.

We claim:

1. A signaling device comprising a motor 75 and a rotary compressor driven thereby and adapted for unitary support, a horn body in combination with a portion of a vehicle body having an opening therethrough, and means of communication between the compressor and the horn body including a tubular member which extends through the opening in the vehicle body and secures the horn body to the vehicle body.

2. A signaling device comprising a motor, 80 a rotary compressor driven thereby, an end cap mounted on the compressor and having a passageway in communication with the pressure side of the compressor, a horn body and a pipe connecting the passageway in the end 85 cap to the horn body, and a sound producing device in connection with the horn body.

3. A signaling device comprising a motor, 90 a rotary compressor driven thereby, an end cap mounted on the compressor and having a passageway in communication with the pressure side of the compressor, a horn body in combination with a wall having an opening therethrough, a pipe connecting the passageway in the end cap to the horn body and including a tubular member securing the horn body to said wall and a sound producing device in connection with the horn body.

4. In a signaling device, the combination 95 with a wall having an opening therein, of a horn body having an inclined base conforming with the inclination of the wall and a conduit for supplying fluid under pressure to the horn body including a tubular nut having a portion extending through said wall 100 and secured to the horn body, and a sound producing device in connection with the horn body.

110 In witness whereof we have hereunto set our hands this 9th day of May, 1927.
